UNITED STATES PATENT OFFICE

KEMPER SLIDELL AND EDWIN M. WYATT, OF MADISON, WISCONSIN, ASSIGNEES, BY
MESNE ASSIGNMENTS, TO AMERICAN FACE BRICK RESEARCH CORPORATION, A
CORPORATION OF ILLINOIS

BUILDING WALL OF CELLULAR BLOCKS

Application filed August 19, 1929. Serial No. 386,843.

This invention relates to a wall constructed of blocks of bloated cellular argillaceous material, such as clay or shale, which has been first broken or ground into particles 5 of comparatively small size and thereafter subjected to a heat treatment at a temperature to cause liquefaction and bloating of the mass, with a resultant unification of the granular particles into a cellular block, the 10 cell walls of which are of vitrified material. An appropriate temperature will in most cases lie within the range of from 2000° F. to 2300° F.

The material, as used in the wall of the 15 present invention, is cut, after leaving the furnace, into building blocks of the desired size and shape. The cutting of the original slab of material into building blocks cuts through the cells so that the cut surfaces 20 which are truly planate are characterized by the presence of minute open cavities or pockets separated by walls of vitrified material.

The cut surfaces which preferably afford 25 the top, bottom, end and rear walls of the completed block present the truly planate and pocketed character above mentioned, but the remaining surface of each block, which constitutes the exterior or exposed 30 surface in the wall of the present invention, is uncut and presents a roughened or pebbled appearance, occasioned by the protrusion caused by the rough or irregular surface 35 of the original layer of granular particles. The exposed surface, however, is continuous or unbroken and possesses an attractive texture and coloration well adapting it to the requirements of an exterior 40 wall surface.

The cut surfaces, on the contrary, being 45 truly planate and cut to exact dimensions, permit the blocks to be accurately laid one upon another without the interposition of relatively thick mortar courses, which in ordinary brickwork are required to compensate for irregularities in the surface contour and dimensions of the bricks.

The blocks of the present invention, 50 furthermore, may be bonded by a thin film

or layer of cementitious material interposed between the blocks, which fills into the open pockets or cavities afforded by cutting through the cells, so that in bonding the blocks of the present invention, any cement 55 applied with a brush, or similar thin cementitious material, may be advantageously employed, and the blocks can be much more rapidly laid than is possible in the laying of brickwork and laid by unskilled labor, 60 since troweling and truing of the courses is not required.

The individual blocks of the present invention are extremely light, impervious to water, of low thermal conductivity, and of 65 sufficient strength to meet building requirements.

The pebbled exterior surface may be colored in attractive shades of buff, tan, or other colors, depending upon the nature of 70 the surface materials employed in the production of the blocks, and the heat and atmospheric treatment to which the material is subjected during the fusing and annealing operations.

The method of producing the material, however, forms no part of the present invention and need not be here described in detail.

In the drawings:

Figure 1 is a perspective view of a wall section composed of the blocks of the present invention, and

Figure 2 is a sectional view showing a plaster coat applied directly to the inner 85 surface of the wall, and

Figure 3 a perspective view of a modification showing the blocks grooved or channelled to break the bonding surfaces.

The blocks A present cut end surfaces B, 90 cut top and bottom surfaces C, and a rear surface D which may or which may not be cut. These cut surfaces expose the cells in the form of open pockets or cavities E.

The front face F of each block presents 95 the natural surface contour and texture occasioned by the vitrification and bloating of the material, which surface, as before stated, is continuous and imperforate, although of a roughened or pebbled texture and of suit-

able coloration to present an attractive wall surface.

The blocks are bonded by a thin film or layer G of cementitious material which fills 5 into the pockets, but at the same time permits the cut planate surfaces to be closely adjoining. These surfaces are afforded by cutting the original slab by means of a carbon-rundum disk or other suitable cutting device 10 which severs the original slab into accurately proportioned blocks, preferably rectangular, which will fit closely and accurately against one another in the building up of the wall structure. Corner bricks, 15 however, may be cut on a diagonal so that by joining the diagonal cuts of such bricks the facing surface A may be exposed continuously at the building corners or at openings.

20 In view of the character of the interior surface of the wall, which is preferably, though not necessarily, afforded by the cut pocketed surfaces of the blocks, and also by reason of the heat insulating capacity of 25 the cellular blocks, and by the imperviousness of the material to the penetration of water, it is possible, with advantage, to apply a plaster coat H directly to the inner surface of the wall, without the provision 30 of laths, furring strips or the like, upon which to lay the plaster coat. If cut surfaces are presented on the interior of the wall, the applied plaster will enter into and tightly bond with the exposed pockets or cavities afforded by the cut cells, but if an uncut surface is presented, it will be of a sufficiently rough texture to afford adhesion for the plaster. It is of course practical and easy to cut or grind grooves or slots K, 40

Fig. 3 into the bonding surface or surfaces so that the mortar or adhesive joint is definitely broken to further reduce any possibility of moisture penetrating through the wall via the adhesive material used.

45 The blocks of the present invention may be made of a thickness commensurate with the original thickness of the bloated slab as it comes from the furnace, and simply cut to give the proper length and width to the 50 blocks, or the original slab may be severed to provide blocks of reduced thickness, but in either case the inner wall surface will be of a character and texture to permit direct adherence of the plaster, although the 55 cellular character of the blocks permits the driving of nails, so that, if desired, furring strips trim or the like may be secured by nailing, particularly if the nails are driven obliquely.

60 We claim:

1. A wall composed of a plurality of blocks of cellular argillaceous material, the cell walls of each block being of vitrified material and the cells being individually formed and non-communicating, the super-

posed surfaces of adjacent blocks being planate and exposing pockets formed by cutting through the cells, and the blocks being bonded by cementitious material filled into the exposed pockets, whereby portions of the adjacent planate surfaces of the blocks may be in substantial contact.

2. A wall composed of a plurality of blocks of cellular argillaceous material, the cell walls of each block being of vitrified material and the cells being individually formed and non-communicating, the superposed surfaces of adjacent blocks being planate and exposing pockets formed by cutting through the cells, and the blocks being bonded by cementitious material filled into the exposed pockets, the exposed surface of the wall being uncut and of imperforate pebbled texture, whereby portions of the adjacent planate surfaces of the blocks may be in substantial contact.

3. A wall composed of a plurality of blocks of cellular argillaceous material, the cell walls of each block being of vitrified material and the cells being individually formed and non-communicating, the superposed surfaces of adjacent blocks being planate and exposing pockets formed by cutting through the cells, and the blocks being bonded by cementitious material filled into the exposed pockets, the exposed surface of the wall being uncut and of imperforate pebbled texture and having a distinctive coloration, whereby portions of the adjacent planate surfaces of the blocks may be in substantial contact.

4. A wall composed of a plurality of blocks of cellular earthy material, the cell walls being of vitrified material and the cells being individually formed and non-communicating, the superposed surfaces of adjacent blocks being planate and exposing pockets formed by cutting through the cells, and the blocks being bonded by a layer of cementitious material filled into the exposed pockets, and at least one of said surfaces being provided with an interior longitudinal groove affording an interior void and breaking the continuity of the bonding layer.

5. A wall composed of a plurality of blocks of cellular argillaceous material, the cell walls being of vitrified material and the cells being individually formed and non-communicating, the superposed surfaces of adjacent blocks being planate and exposing pockets formed by cutting through the cells, and the blocks being bonded by an interposed layer of cementitious material filled into the exposed pockets, the inner surfaces of the blocks composing the wall being planate and exposing pockets formed by cutting through the cells, and a coating of plaster adhering directly to the inner pocketed surfaces of the blocks composing the wall.

6. A wall composed of a plurality of

blocks of cellular argillaceous material, the cell walls being of vitrified material and the cells being individually formed and non-communicating, the superposed surfaces of adjacent blocks being planate and exposing pockets formed by cutting through the cells, and the blocks being bonded by an interposed layer of cementitious material filled into the exposed pockets, the inner surfaces 10 of the blocks composing the wall being planate and exposing pockets formed by cutting through the cells, and a coating of plaster adhering directly to the inner pocketed surfaces of the blocks composing the wall, 15 the outer exposed surface of the wall being uncut and of imperforate pebbled texture.

In witness that we claim the foregoing, we have hereunto subscribed our names this 26th day of July, 1929.
